CLAIM

The ornamental design for an adjustable fastening buckle for snorkel as shown and described.

DESCRIPTION

FIG. 1 is a front elevational view of an adjustable fastening buckle for snorkel showing my new design;

FIG. 2 is a rear elevational view thereof;

FIG. 3 is a left side view thereof;

FIG. 4 is a right side view thereof;

FIG. 5 is a bottom plan view thereof;

FIG. 6 is a top plan view thereof;

FIG. 7 is a perspective view thereof;

FIG. 8 is a second perspective view thereof;

FIG. 9 is a third perspective view thereof;

FIG. 10 is a fourth perspective view thereof;

FIG. 11 is a perspective view in folded state;

FIG. 12 is a second perspective view in folded state;

FIG. 13 is a third perspective view in folded state; and,

FIG. 14 is a fourth perspective view in folded state.

The broken lines illustrate portions of the adjustable fastening buckle for snorkel that form no part of the claimed design.

1 Claim, 14 Drawing Sheets
